UNITED STATES PATENT OFFICE.

HARRY RAYMOND COLLINS, OF ALLENTEWON, PENNSYLVANIA, ASSIGNOR TO FULLER-LEHIGH COMPANY, A CORPORATION OF PENNSYLVANIA.

FEEDING APPARATUS.

Original application filed November 8, 1919, Serial No. 336,571. Divided and this application filed February 7, 1924. Serial No. 691,100.

To all whom it may concern:

Be it known that I, HARRY RAYMOND COLLINS, a citizen of the United States, residing at Allentown, in the county of Lehigh, State of Pennsylvania, have invented certain new and useful Improvements in Feeding Apparatus; and I do hereby declare the following to be a full, clear, and exact description of the invention, such 10 as will enable others skilled in the art to which it appertains to make and use the same.

This invention relates to feeding apparatus for feeding pulverulent or granular material and is directed particularly to the provision of a feeding apparatus of an improved form adapted for use in supplying fine material to apparatus which is to act upon the material, such for instance as a 20 grinding mill.

The invention is of special value in feeding apparatus for feeding fine coal to a pulverizer mill in which the coal is reduced to a pulverized state suitable for use in a 25 pulverized fuel furnace. One object of the invention is to provide a feeder of a simple construction such that it may be manufactured at low cost, and capable of convenient adjustment whereby the rate at which the 30 material is supplied to the mill may be regulated over a wide range quite readily.

Another object of the invention is to provide a feeder of this character adapted for use in connection with mills of the type known as air separation mills, in which it is important that the feeder be of such a construction as will preclude the entrance or escape of air to or from the mill through the feeding apparatus. In some forms of 35 mills for pulverizing coal, the fine particles are drawn out by an air circulation to a suitable separator and the air from the separator is returned to the mill to pick up a further supply of the fine particles. In a mill 40 of this type, the material to be pulverized must be fed in practically continuously but it is very important that there should be no entrance of air to or escape of air from the mill through the feeder.

50 These objects are attained in accordance with the present invention by the provision of a feeder having a reciprocating member and parts associated therewith of such a construction that when the member is recip-

rocated in one direction some of the material 55 to be fed is allowed to fall by gravity into its path of movement and when the member is reciprocated in the other direction, a portion of the material to be fed lying in its path is pushed by the member forward to a 60 position where it will pass by gravity into the mill, an adequate supply of the material to be fed being always maintained in the path of movement of the material so that this material itself will serve as an effective 65 obstruction to the passage of air into or out of the mill through the feeder.

In a feeder of this type, adequate means must be provided for effecting an adjustment of the rate of feed of the material. 70 This may be accomplished in various ways, for instance, the range over which the member referred to is reciprocated may be adjusted as to its length or as to its angular position, as a result of which a greater or 75 less amount of the material will be moved forward to the position at which it drops by gravity by each feeding movement of the reciprocating member. Instead of this, provision may be made for regulating as desired the freedom with which the material falls into the path of movement of the reciprocating member so as to regulate the rate of feed in that way.

These features of the invention will be 85 better understood by reference to the following description taken in connection with the accompanying drawings which illustrate the preferred embodiment of the invention. In these drawings, Fig. 1 is a central vertical section of the feeding apparatus and a portion of a ball mill supplied by the apparatus and Fig. 2 is an elevation of a portion of the apparatus shown in Fig. 1.

Referring to these drawings, a ball mill 95 is shown of the type commonly used in pulverizing coal for use in a pulverized fuel furnace, cement kiln or the like. It includes a grinding ring 3 and balls 4 which are caused to travel around in the ring by pusher 100 arms 5 mounted on a central power-driven shaft 6. Scoops or blades 7 serve to throw the pulverized material upward to suitable separating means. The mill shown in the present instance is of the air separation type including an adjustable damper 8 through 105 which the air laden with the pulverized material is drawn by a fan located above

the damper. The air passes from the mill to a separator where the pulverized material is collected from it and then the air returns to the mill by way of a duct 9.

5 The feeding apparatus is employed for feeding the material to be ground in through the passage 10 where it drops down within the casing to the grinding ring 3.

The feeder includes a casing consisting of 10 side walls 11 of semi-circular form and a bottom wall 12 which is curved as shown. This casing is mounted upon a bracket 13 secured to the casing of the mill and having the passage 10 formed therein. An outlet 15 from the casing of the feeder aligns with this passage 10. Within the casing of the feeder is a reciprocating member having semi-circular side walls 14, a curved bottom wall 15 and a wall 16 which is disposed radially and is spaced from the adjacent end of the curved wall 15. This wall 16 is of such length that its edge lies close to the surface of the curved wall 12 of the casing, so that when this member is reciprocated, the edge 20 of wall 16 sweeps over the curved wall 12 and pushes forward any material lying thereon. This reciprocating member is pivotally mounted in bearings formed upon the side walls 11 of the casing of the feeder 25 and is adapted to be reciprocated about its pivot. A hopper 17 extends down into the reciprocating member as shown, and on one side this hopper is provided with a door 18 to give access to the interior of the feeder 30 for inspection and repair. The hopper is bolted upon the casing of the feeder with certain of its walls forming part of the casing as shown in the drawing. The hopper may be provided with a gate 19 adapted to 35 be mounted upon the inclined wall of the hopper and capable of adjustment and of being secured in any position of adjustment upon that inclined wall.

The operating mechanism is shown in Fig. 45 2. A belt 20 transmits power from a power shaft to a counter-shaft 21, and a belt 22 transmits power from that shaft to another shaft 23. On this shaft 23 is a crank or eccentric 24 with which cooperates a rod 50 25. The opposite end of this rod 25 is connected to a crank arm 26 mounted upon the end of the shaft 27 upon which the reciprocating member of the feeder is mounted. The crank arm 26 is preferably provided 55 with a slot as shown in Fig. 2 whereby the rod 25 may be connected to the arm 26 in various positions of adjustment with respect to the shaft 27.

When the mill is in operation, the shaft 27 60 is reciprocated by the rod 25 and crank arm 26 and with it the reciprocating member of the feeder consisting of the parts 14, 15 and 16. Fig. 1 shows these reciprocating parts at practically one end of their range of movement. In this position the pulverized

material drops by gravity through the opening between the walls 15 and 16 down upon the curved wall 12 of the feeder. When the reciprocating member moves to the left, the radial wall 16 engages the 70 material lying in front of it and pushes it forward, and while it does so more or less of the material falls through the outlet passage of the feeder and the passage 10 into the mill. The range of reciprocation of the 75 radial wall 16 is such that the limit of its movement toward the outlet is spaced from the latter so that not all of the material on the wall 12 is discharged into the outlet by the movement toward the latter of the radial wall. Then on the return movement of these reciprocating parts more of the material to be pulverized drops down upon the wall 12 to replenish the supply there. At 80 all times there is a sufficient amount of the material upon the wall 12 and between that wall and the wall 15 to effectually preclude the passage of air either way through the feeding apparatus. The rate of feed may be regulated as desired, as for instance by 85 regulating the range of the reciprocating parts of the feeder by changing the point of connection of the rod 25 to the crank arm 26. A similar adjustment can be effected by 90 altering the position of the gate 19 and thus regulating the freedom of flow of the material down through the hopper and upon the wall 12.

This application constitutes a division of 95 an application for patent filed by me on November 8th, 1919, on which Patent No. 1,484,298 was issued Feb. 19, 1924.

I claim:

1. A feeder comprising the combination of 100 a casing provided with an inlet opening, a curved wall and an outlet opening leading from that wall, a reciprocating member comprising a portion lying between the curved wall and the inlet opening, and normally intercepting material entering the casing through the inlet opening and operable to discharge this material upon the curved wall by the reciprocation of said member, and a second portion movable over the 105 curved wall and operable to engage and move toward the outlet opening material discharged upon the curved wall from the first portion, and power devices for actuating the reciprocating member through a range such that the limit of travel toward the outlet opening of the second portion thereof is spaced from said outlet opening.

2. A feeder comprising the combination of 110 a casing provided with an inlet opening, a curved wall and an outlet passage, a feeding member comprising a portion lying between the curved wall and the inlet opening and normally intercepting material entering the casing through the inlet opening, this portion 115 preventing the direct passage of ma- 120

terial from the inlet to the outlet through the casing and being operable to discharge the intercepted material upon the curved wall by the reciprocation of said member, 5 and a second portion adapted to engage and move toward the outlet opening material discharged upon the curved wall from the first portion, and means for reciprocating said feeding member within the casing through a 10 range such that the limit of travel of the second portion toward said outlet opening is spaced therefrom.

3. A feeder comprising the combination of a casing provided with an inlet opening, 15 a curved wall and an outlet leading therefrom, a reciprocating member comprising a portion lying between the inlet opening and the curved wall and normally intercepting the material entering the casing through the 20 inlet opening, this portion serving to prevent the direct flow of material from the inlet opening to the outlet opening through the casing and being operable to discharge the intercepted material upon the curved wall by the reciprocation of said member, and 25 a second portion disposed in spaced relation to said first portion and movable over the curved wall to engage and move toward the outlet material discharged upon the curved wall from the first portion, power mechanism connected to the member for causing 30 its reciprocation, and means for adjusting the range of reciprocation of said member, this range of reciprocation always being such that the limit of travel of the second 35 portion toward said outlet opening lies at a point on said curved wall spaced from said outlet opening.

4. A feeder comprising the combination of 40 a casing provided with an inlet opening, a curved wall and an outlet leading therefrom, a member adapted to move in said casing with a reciprocating motion and comprising an arcuate portion lying in spaced relation 45 from the said curved wall and normally intercepting material entering the casing through the inlet opening, the said arcuate member being so formed as to discharge the material thereon upon the curved wall as 50 the member reciprocates and normally preventing the direct flow of material from the inlet opening to the outlet opening, and a second portion spaced from one end of the first portion and operable to engage and move material discharged upon the curved wall from said arcuate portion, power devices for reciprocating said member through 55 a range such that the limit of travel of the second portion thereof toward the outlet opening is always spaced therefrom whereby a supply of material always remains upon said curved wall to preclude the passage of air through said feeder, and means for regulating the rate at which material is fed 60 through the outlet by the reciprocation of 65

said member by varying the range through which the member reciprocates.

5. A feeder comprising the combination of a casing provided with a curved wall and an outlet leading therefrom, a reciprocating member comprising a curved wall spaced from the curved wall of the casing and a substantially radial wall spaced from the curved wall, and means for reciprocating the 70 said member to cause the radial wall to move over the curved wall of the casing to move material supplied to the casing through the space between the curved wall and the radial wall of the member.

6. A feeder comprising the combination of a casing having a curved wall and an outlet leading therefrom, a reciprocating member comprising a curved wall spaced from the curved wall of the casing and a substantially radial wall spaced from the curved 75 wall, and means for reciprocating said member to cause the radial wall to move back and forth over a portion of the curved wall of the casing spaced from said outlet.

7. A feeder comprising the combination of a casing having a curved wall and an outlet leading therefrom, a reciprocating member comprising a curved wall spaced from the curved wall of the casing and a substantially radial wall spaced from the curved wall, means for reciprocating said member to cause the radial wall to move back and forth over a portion of the curved wall of the casing spaced from said outlet and means for effecting an adjustment of the rate at 90 which the material is supplied to said outlet by the reciprocations of said radial wall.

8. A feeder comprising the combination of a casing having a curved wall and an outlet leading therefrom, a reciprocating member comprising a curved wall spaced from the curved wall of the casing and a substantially radial wall spaced from the curved wall, means for reciprocating said member to cause the radial wall to move back and forth over a portion of the curved wall of the casing spaced from said outlet and means for effecting an adjustment of the rate at which the material is supplied to said outlet by 95 adjusting the range over which the said radial wall is reciprocated.

9. A feeder comprising the combination of a casing provided with a curved wall and an outlet leading therefrom, a reciprocating member provided with a curved wall spaced from the curved wall of the casing and a substantially radial wall spaced from the curved wall, a hopper arranged over said member for supplying the material to be fed to the interior of the member and means for reciprocating the member about the axis of said curved walls, the range of reciprocation of said radial wall being spaced from the outlet from the casing.

10. A feeder comprising the combination 130

- of a casing having an outlet in one wall thereof, an inlet in the casing, reciprocating means movable over the wall of the casing in which the outlet is located to engage material thereon and move it toward the outlet, the limit of movement of the reciprocating means toward the outlet being spaced from the latter and means interposed between the inlet and the said wall for intercepting material entering the casing through the inlet, this means being movable in correspondence with the movement of the reciprocating means to discharge the material so intercepted upon said wall.
- 15 11. A feeder comprising the combination of a casing having a wall over which the material to be fed is moved and an outlet from

said wall, a reciprocatory member comprising a wall substantially parallel to and spaced from the said wall of the casing and 20 a second wall spaced from the said wall of the member and substantially perpendicular to the said wall of the casing, power devices for reciprocating the said member to cause the said transverse wall to move over the 25 surface of the said wall of the casing over a range spaced from the outlet, and means for supplying the material to be fed to said member so as to cause it to pass by gravity through the space between the two said walls 30 of the member.

In testimony whereof I affix my signature.

HARRY RAYMOND COLLINS.
